(57) CLAIM

The ornamental design for a ball hitting tee, as shown and described.

DESCRIPTION

FIG. 1 is a front perspective view of a ball hitting tee showing my new design;

FIG. 2 is a rear view thereof;

FIG. 3 is a plan view thereof;

FIG. 4 is a side view thereof, the opposite side being a mirror image;

FIG. 5 is a front perspective view similar to FIG. 1, showing in broken lines the tee post in upstanding position and the storage straps; and,

FIG. 6 is a front perspective view similar to FIG. 5, showing in broken lines the tee post in storage position under the storage straps.

The broken line showing of the circular aperture, tee post and storage straps is for illustrative purposes only and forms no part of the claimed design.
